(57) CLAIM

The ornamental design for a table, as shown and described.

DESCRIPTION

FIG. 1 is a front, right, upper perspective view of a table embodying my new design;

FIG. 2 is a front elevational view thereof, the rear elevational view being identical to the front elevational view;

FIG. 3 is a right side elevational view thereof, the left side elevational view being identical to the right side elevational view; and,

FIG. 4 is a top view thereof.

1 Claim, 2 Drawing Sheets

FIG. 1

FIG. 2
